UNITED STATES PATENT OFFICE.

JACOB LEWIS BROSCHEART, OF TRENTON, MISSOURI.

PIPE-COUPING.

1,391,456.

Specification of Letters Patent. Patented Sept. 20, 1921.

Application filed July 25, 1919, Serial No. 313,267. Renewed March 22, 1921. Serial No. 454,416.

To all whom it may concern:

Be it known that I, JACOB LEWIS BROSCHEART, a citizen of the United States, residing at Trenton, in the county of Grundy, 5 State of Missouri, have invented a new and useful Pipe-Coupling; and I do hereby declare the following to be a full, clear, and exact description of the invention, such as will enable others skilled in the art to which 10 it appertains to make and use the same.

The invention relates to pipe couplings and particularly to a coupling adapted for emergency use in connection with train or steam lines of passenger or freight trains, 15 it being the principal object to provide a coupling which may be easily and quickly applied to the adjacent ends of a broken train line, thereby allowing the use of the brakes or steam line until the train reaches 20 a point where a permanent repairing of the train line may be made.

A further object is to provide an emergency coupling which will be compact in form and may be carried on every train, 25 also to provide the ends of the coupling with means for expanding gaskets into air-tight engagement with the interior of the adjacent ends of a broken train line, said gaskets also being additionally forced out- 30 wardly by the pressure of the air within the train line when the coupling is in place.

With the above and other objects in view the invention resides in the combination and arrangement of parts as hereinafter set 35 forth shown in the drawings, described and claimed, it being understood that changes in the precise embodiment of the invention may be made within the scope of what is claimed without departing from the spirit 40 of the invention.

In the drawings:—

Figure 1 is a sectional view through the adjacent ends of a broken train line, showing the coupling applied thereto and in elevation. 45

Fig. 2 is a view similar to Fig. 1 but showing the coupling in section.

Fig. 3 is a sectional view taken on line 3—3 of Fig. 1.

Referring to the drawings, the numeral 1 designates a conventional form of train line which may be of a steam or air type, said train line 1 having been broken thereby forming ends 2 and 3, which breaking 50 of the train line will cause a loss of pressure thereby placing the brakes out of control

of the operator of the train. To temporarily connect the ends 2 and 3 the emergency coupling 4 is provided, which coupling comprises the tubular member 5 which is externally threaded as at 6, and threaded on said tubular member are jamming sleeves 7, which jamming sleeves have their outer ends 8 engaging rings 9, which rings are adapted to jam against the sides of gaskets 10. The outer edges of the gaskets 10 engage as at 11 sleeves 12, which sleeves form means for buckling the gaskets 10 so that their outer faces will be forced outwardly into engagement with the interior walls of 70 the ends 2 and 3 of the pipe line. Edges 13 of the sleeves 12 engage the edges of gaskets 14 and are adapted to force said gasket 14 against the rings 15 which are threaded on the ends of the tubular member 75 5, said rings 15 being prevented from rotation on the tubular member 5 by means of keys 16.

It will be seen that when the jamming sleeves 17 are threaded toward the ends of 80 the tubular member 5 that the ends 8 of the jamming sleeves will freely rotate and force outwardly against the engaging rings 9 which action will cause the gaskets 10 to be forced against the edges of the sleeves 85 12, the other edges of the sleeves 12 will be forced against the inner edges of the gaskets 14, which gaskets are prevented from end movement by means of the rings 15, thus it will be seen that gaskets 10 and 14, at 90 each end of the coupling member will be compressed and forced outwardly into engagement with the walls of the ends 2 and 3 of the pipe line 1, thereby securely joining 95 said ends and at the same time preventing leakage. To additionally assure the proper engagement of the gaskets 14 the ends of the tubular member 5 are provided with apertures 17, said apertures 17 being in registration with the inner face of the 100 gaskets 14, and through apertures 17 the pressure within the pipe line comes in direct contact with the gaskets in such a way as to force them outwardly into engagement with the inner walls of the ends 2 and 3. 105 It will be seen that if the gaskets 14 have not been compressed and expanded enough that the air pressure will furnish the necessary additional expansion. Also that if the joint is a poor one the pressure will extend 110 around the threads which are in registration with the inner wall of the gaskets 14.

From the above it will be seen that a coupling will be provided which is positive in its action, easily applied and one wherein the delay to a train is reduced to a minimum, which is a considerable item of expense and danger.

The invention having been set forth what is claimed as new and useful is:—

1. In an emergency coupling, the combination with the adjacent ends of a broken pipe, of a tubular pipe section exteriorly threaded and telescoping the adjacent ends in spaced relation to their interiors, a holding member on each end of the pipe section, gaskets on the ends of the tubular pipe section inside of the holding members, jamming sleeves threaded on the tubular member and substantially centrally of said member and forming means for compressing and expanding the gaskets into engagement with the interior wall of the pipe ends and apertures in the ends of the tubular members and adjacent the gaskets, whereby the interior pressure within the pipe line may additionally expand the gaskets.

2. In an emergency coupling, the combination with the adjacent ends of the broken pipe, of a tubular pipe section exteriorly threaded and telescoping the adjacent ends in spaced relation to their interiors, a holding collar threaded on each end of the pipe sections, gaskets on each end of the tubular section, one of said gaskets being adjacent the coöperative holding collar, a metallic ring disposed between the gaskets at each end of the tubular pipe section, jamming sleeves threaded on the tubular pipe section and adapted to be threaded toward the ends of the same for compressing the gaskets be-

tween the metallic sleeves, the holding collars and said jamming sleeves, and apertures in the ends of the tubular pipe section and in registration with the gaskets, whereby the pressure within the pipe line may be utilized for additionally expanding the gaskets into engagement with the interior walls of the adjacent ends of the broken pipe line.

3. In an emergency coupling, the combination with the adjacent ends of a broken pipe, of a tubular pipe section exteriorly threaded and telescoping the adjacent ends in spaced relation to their interiors, a holding collar threaded on each end of the pipe section, gaskets on each end of the tubular section, one of said gaskets being adjacent the coöperative holding collar, metallic rings disposed between the gaskets, metallic rings engaging the inner edges of the inner gaskets, jamming sleeves engaging the last named metallic rings and adapted to force said metallic rings at each end outwardly for expanding the gaskets circumferentially between the metallic rings disposed between said gaskets and the collars at the ends of the pipe section, and apertures in the wall of the pipe section in registration with the outer gaskets whereby pressure within the pipe will be allowed to expand the gaskets outwardly for additionally insuring an air tight joint.

In testimony whereof I have signed my name to this specification in the presence of two subscribing witnesses.

JACOB LEWIS BROSCHART.
